UNITED STATES PATENT OFFICE.

SALVADOR DE GOMILA, OF MALAGA, SPAIN, ASSIGNOR TO JULIUS WELTER, OF MALAGA, SPAIN.

MULTIPLYING DEVICE.

No. 807,550.

Specification of Letters Patent.

Patented Dec. 19, 1905.

Application filed June 8, 1905. Serial No. 264,280.

To all whom it may concern:

Be it known that I, SALVADOR DE GOMILA, a subject of the King of Spain, and a resident of Malaga, Spain, have invented certain new and useful Improvements in Multiplying Devices, of which the following is a specification.

The present invention relates to a multiplying device in which the numbers of the products printed upon endless bands appear in looking-openings of the front wall of the apparatus and are read under the multiplicands.

The novelty of this device especially consists in that the shaft driving the endless bands is connected by an intermediate shaft with the wheel carrying the band which is placed on the figures of the multiplier.

In the annexed drawings, Figure 1 is a view of a plurality of panes which are located in the front wall of the apparatus. Fig. 2 shows the interior parts of the device, partially in front view, partially in section. Fig. 3 is a top plan view of the multiplier-disk. Fig. 4 shows a plan view of the beginning parts of the product-tables. Fig. 5 shows a writing-table intended to be arranged on the side of the multiplier-disk.

The front side of the apparatus seen by the user is divided, as shown by Fig. 1, with four superposed cases or panes, which are divided in twenty-five strips, all divided each into two rectangles by a horizontal line. In the latter are arranged, in a continuous order, the figures "1" until "100." Within each of these rectangles is cut out, adjacent to the said horizontal center line, a looking-opening through which the numbers carried by the product-tables may be seen. These product-tables are formed of endless bands 1, Fig. 2 and 4, upon which are written or printed the necessary numbers in the order shown by Fig. 4. The number of the bands is four. They are wound upon four pairs of rollers carrying pins, preventing the bands from slipping to one side or the other. The shafts of these rollers are supported in a convenient manner in a framework, each of the anterior rollers carrying on one side a bevel-wheel h , meshing with a bevel-wheel i , keyed upon the vertical shaft h . The lowermost bevel-wheel of this shaft meshes with a similar one keyed on the horizontal shaft g , the second wheel of which meshes, in turn, with a wheel keyed on the shaft of hand c , which is intended to be put on the numbers of

the multiplier. The hand, provided with an operating-knob and a guide-pin d , may be rotated on a horizontal disk b , arranged in front of the front wall of the apparatus and on which are written on a circular line the multipliers "1" to "100." The multiplier may be seen through a little aperture arranged in the band. When, for instance, the multiplication "48 $\times$ 96" is to be executed, all that is to be done is to put simply the lever c on the number "48" (this has been done in the position shown in the drawings) and then the product "4608" may be read on the front wall of the apparatus at "96." When more complicated multiplications are to be executed, the additions are effected on the table shown in Fig. 5, in the panes of which the numbers appearing in the looking-openings are written in a diagonal direction from the left top to the right bottom, according to the lines of the table. Then the addition is effected. If, therefore, "48" is to be multiplied with "6'462'818'399," the material may readily read on the front wall of the apparatus, and the product obtained and written in the columns of the table is: "310'215'283'152." For this multiplication the numbers of the double squares are to be read in the openings provided in the front wall of the apparatus. These numbers are read in their natural order, as shown by the following scheme:

Case with multiplier on the front wall.	Numbers of the double squares to be considered in for the addition table.	85
99	47 / / 52	90
83	39 / / 84	
81	38 / / 88	
62	29 / / 76	95
64	30 / / 72	

When the entire multiplication "6462818399 $\times$ 896548," comprising thousands of millions and shown, by way of example, in Fig. 5, is to be executed besides the above-described operation, the hand is still to be operated two times. It must first be adjusted on the number "65" and then on the number "89." 100 105

The products read in the double squares are, in both cases, transferred into the addition-table.

Having now fully described my said invention, what I claim, and desire to secure by Letters Patent, is—

A computing-machine comprising a plurality of endless bands, a plurality of rollers upon which said bands are mounted, bevel gear-wheels mounted upon the ends of the rollers which are located at one end of the bands, a shaft, a plurality of bevel gear-wheels mounted upon said shaft, one of said gear-wheels meshing with each of the gear-wheels of the rollers, a bevel gear-wheel located adjacent the lower end of the shaft, a horizontal shaft,

a bevel gear-wheel mounted at one end of said shaft and meshing with the gear-wheel adjacent the lower end of the first-named shaft, a vertical shaft, gear-wheels located between said vertical and horizontal shafts, a plate bearing the multipliers and a hand-actuated lever mounted upon the vertical shaft and having an opening formed therein, adapted to register with the said multipliers.

In testimony whereof I have hereunto set my hand in presence of two witnesses.

SALVADOR DE GOMILA.
